(57) **CLAIM**

The ornamental design for a controller for railway vehicle, as shown and described.

DESCRIPTION

FIG. 1. is a perspective view of front, left and top plan side of a controller for railway vehicle showing our new design;

FIG. 2. is a front view thereof;

FIG. 3. is a rear view thereof;

FIG. 4. is a left side view thereof;

FIG. 5. is a right side view thereof,

FIG. 6. is a top plan view thereof; and,

FIG. 7. is a bottom plan view thereof.

The portions of the article in broken lines show unclaimed subject matter only and form no part of the claimed design.
